CLAIM

I claim the ornamental design for a combination surgical spinal dilator and retractor system, as shown and described.

DESCRIPTION

FIG. 1 is a perspective view of a combination surgical spinal dilator and retractor system, showing my new design;
 FIG. 2 is a top plan view of the combination surgical spinal dilator and retractor system of FIG. 1;
 FIG. 3 is a bottom plan view of the combination surgical spinal dilator and retractor system of FIG. 1;
 FIG. 4 is a right side elevational view of the combination surgical spinal dilator and retractor system of FIG. 1;
 FIG. 5 is a left side elevational view of the combination surgical spinal dilator and retractor system of FIG. 1;
 FIG. 6 is a front elevational view of the combination surgical spinal dilator and retractor system of FIG. 1;
 FIG. 7 is a rear elevational view of the combination surgical spinal dilator and retractor system of FIG. 1;
 FIG. 8 is a perspective view of a combination surgical spinal dilator and retractor system of FIG. 1, showing the retractor blade removed in order to show clarity and completeness of disclosure;
 FIG. 9 is a right side elevational view of the combination surgical spinal dilator and retractor system of FIG. 8;
 FIG. 10 is a left side elevational view of the combination surgical spinal dilator and retractor system of FIG. 8;
 FIG. 11 is a front elevational view of the combination surgical spinal dilator and retractor system of FIG. 8;
 FIG. 12 is a rear elevational view of the combination surgical spinal dilator and retractor system of FIG. 8;
 FIG. 13 is a top plan view of the combination surgical spinal dilator and retractor system of FIG. 8;
 FIG. 14 is a bottom plan view of the combination surgical spinal dilator and retractor system of FIG. 8;
 FIG. 15 is a perspective view of a combination surgical spinal dilator and retractor system of FIG. 1, showing the dilator removed in order to show clarity and completeness of disclosure;
 FIG. 16 is a right side elevational view of the combination surgical spinal dilator and retractor system of FIG. 15;
 FIG. 17 is a left side elevational view of the combination surgical spinal dilator and retractor system of FIG. 15;
 FIG. 18 is a front elevational view of the combination surgical spinal dilator and retractor system of FIG. 15;
 FIG. 19 is a rear elevational view of the combination surgical spinal dilator and retractor system of FIG. 15;

FIG. 20 is a bottom plan view of the combination surgical spinal dilator and retractor system of FIG. 15; and, FIG. 21 is a top plan view of the combination surgical spinal dilator and retractor system of FIG. 15.

The broken lines immediately adjacent to the full line showing of the claimed design represent the bounds of the claimed design while all other broken lines are directed to environment and are for illustrative purposes only; the broken lines form no part of the claimed design.
